UNITED STATES PATENT OFFICE.

ROBERT ALEXANDER, OF OAKLAND, CALIFORNIA.

METHOD OF PAINTING ON VELVET OR OTHER CUT PILE FABRIC.

No Drawing.

Application filed May 20, 1925. Serial No. 31,694.

My invention comprises a method of painting on velvet or other cut pile fabric having a suitable nap and the resulting product. An object of my invention is to produce an artistic painting on a piled fabric so that the fabric may be utilized in draperies, being folded and crushed and unfolded without injuring or spoiling the painting. Another object is to produce an artistic painted fabric which with different lay of the nap will give varied effects. A further object is to so paint on a piled fabric, such as velvet, so that different appearances will be given to the painting when viewed from different directions.

In order to obtain these effects and to produce a useful as well as artistic work, I utilize fabrics having a suitable nap or cut pile, such as velvet, plush, velvet tapestry. 20 Velveteen may also be used as well as the plain cut pile fabrics.

My method of painting and the article produced may be ascertained from the following description directed towards a procedure in working on the velvet to produce a painting which not only has an artistic effect, but may be so made as to simulate a velvet tapestry:

As is well known, good velvet—preferably 30 a silk velvet—has a rather close cut pile or nap, and the nap has a certain lay in which it has a smooth feel when brushed in the direction of the lay and a rough feel when brushed opposite to or across the lay. In 35 the natural velvet the nap or pile lies in the direction of the lay in which a certain amount of the short stubby threads are visible on their sides. When brushed opposite to the lay the threads are more or less on 40 end or bent backwardly.

In proceeding to paint on velvet I utilize 45 paints known as "bronzes" that is, so-called "metallic paints." These are preferably used in powder form and a mixture is made of shellac and alcohol (which may be either grain or wood alcohol). I generally utilize these in the proportion of two-thirds shellac to one-third alcohol. The various colors are obtained by using "bronzes" powders of the 50 proper colors or by combining the colors to secure the desired tint. Artists' brushes of different shapes and types may be used in accordance with the style of work. The brushes are dipped into the solution of shellac and alcohol above mentioned, a small 55 amount of bronze is picked up with a damp

brush and worked on a palette to the proper consistency when it is applied to the velvet.

The velvet is preferably stretched or laid on a table or in a frame on an artist's easel, 60 it is carefully brushed to secure the lay of the pile in the natural manner of the velvet. If the article produced is to be used as a drapery or dress the painting would be made with the pile or nap running from top to 65 bottom.

A drawing of the design to be painted is then sketched on the velvet with any suitable chalk or ready removable crayon. The painting may be done directly with the 70 painting brush by working against the pile. This raises the nap or pile and causes the 75 bronze to adhere to the side of the upturned pile. To secure a more decided effect it is preferable to brush the pile in the reverse 80 direction before applying the paint with the paint brush. This may be done by using a velvet pad or some similar stiff brush. The pile may also be brushed from one side or the other before or during the painting in 85 order to apply the bronzes to the sides of the threads of the pile. To secure high-lights or the effect of projecting or standing out parts of the design, the painting may be made downwardly on the pile so as to naturally 90 cover more of the threads.

After the painting is made in the above manner by successive applications of the same or different colors in accordance with the intention of the artist, or the design he 95 is following, the velvet and painting is carefully brushed in the direction of the lay of the nap to smooth the whole of the fabric. If the effect desired is not obtained by an over-brilliancy or the use of too much paint, 95 this may be rubbed off in the parts desired by brushing the velvet against or with the lay of the pile or crossways thereto. If it is desired to heighten the color in any places the pile may be brushed back and more 100 bronze applied.

I may utilize brocaded velvets and paint in the design formed by the brocading in the above manner by brushing against the lay of the nap so as to deposit the minute particles 105 of the paint or bronze on the threads of the pile.

In order to give a different effect to the painting when viewed from different directions the velvet may be painted as follows: 110 After being thoroughly smoothed a design may be painted by brushing downwardly

on the pile with very thin paints so as to make a flat deposit of the paint or bronze on the smooth threads of the pile. The painting thus produced may be thoroughly 5 brushed in the reverse direction to obtain as well as possible a reversed effect of the pile and a painting with different tones or colors, or possibly a different design may be worked thereon. With some velvets this reverse 10 brushing may be done with a paint brush. The velvet will then be brushed from one side to the other in order to cause the pile to lay crossways to their natural position and still different tones of colors may be 15 used. This type of painting gives an excellent effect when used with long pile fabrics such as plush or velours, and gives a very artistic effect when used as draperies as the folding of the fabric and the brush- 20 ing by drawing aside portières or the like shift the lay of the pile and thus expose different colors as well as different types of paint, giving varied effects.

It is manifest that fabrics having a wool, 25 cotton or other types of thread may be utilized as well as those having silk thread, such as genuine velvet. The material used for the base of the painting would, of course, depend upon the effect desired as well as 30 the monetary value of the resulting painting. It is obvious by using a fabric having a very long nap that interesting and peculiar effects may be obtained by brushing and holding the nap in different directions while 35 the design is painted thereon. As the bronze or similar character paints will cling tightly to most the fabric, carpets and rugs

may be formed in the manner above described, utilizing a base fabric having a suitable type and length of pile. 40

My invention not only includes painting on a pile fabric but comprehends dyeing fabrics in different designs or utilizing dyes and applying them to preferably a plain color base fabric in the direction of the lay 45 of the pile or opposite thereto or crossways if desired. In this type of dyeing designs on fabrics it is preferable to use thin tint colors and gradually apply these until sufficient depth of color is obtained. 50

It is thus manifest that my invention in the method of painting, coating or dyeing piled fabrics may be considerably varied and that the works and articles produced may have quite distinct and different characteristics. 55

Having described my invention, what I claim is:—

1. The method of applying color effects of varying hues to cut pile fabric of the character described which consists in brushing paint into the material in the direction of the lay of the pile and against the lay of the pile in separate steps. 60

2. The method of applying color effects of varying hues to cut pile fabric of the character described which consists in brushing paint into the material in the direction of the lay of the pile and against the lay of the pile and crosswise to the lay in separate 70 steps.

In testimony whereof I affix my signature.

ROBERT ALEXANDER.
